UNITED STATES PATENT OFFICE.

FRANK M. PIERCE, OF CHICAGO, ILLINOIS.

GYROSCOPIC TOY.

Application filed May 31, 1923. Serial No. 642,393.

This invention relates to toys or amusement devices of the gyroscopic type wherein motion is applied to the flywheel by means of a cord wound and unwound upon the hub 5 of the wheel in such a manner as to reverse the direction of rotation of the wheel each time the cord is pulled.

Heretofore, toys of the general type outlined above have been produced in a multiplicity of forms. It is an object of this invention to improve upon the existing types in several ways which will be brought out in detail hereinafter.

It is an object of this invention to provide 15 a device of the class described wherein the operating cord is always in place, yet can be operated as often or as little as desired. By providing the device of this invention with a free ring or loop of the cord on one 20 side of the wheel, the cord can be held free from the wheel after starting the rotation thereof so that the wheel can be allowed to gradually run down without releasing the cord, if so desired.

25 It is another object of this invention to combine a sound producing device with the gyroscope whereby if the cord is allowed to wind up on the hub and is then released, the free end of the cord will strike the sounding 30 device at each revolution of the gyroscope.

It is an important object of this invention to provide a device of the kind described wherein means are provided affording an automatic take-up or re-winding of the propelling means.

35 Other and further important objects of this invention will be apparent from the disclosures in the specification and accompanying drawings.

40 This invention (in a preferred form) is illustrated in the drawings and hereinafter more fully described.

On the drawings:

45 Fig. 1 is a side view of one form of a device embodying features of this invention.

Fig. 2 is a view similar to Fig. 1, with the operating cord wound onto the hub or spacer alongside the gyroscope in a position to start the rotation thereof.

50 Fig. 3 is a partial section of a slightly modified form.

Fig. 4 is an end view corresponding to Fig. 1, with parts omitted.

Fig. 5 is an end view corresponding to Fig. 2 with parts omitted.

Fig. 6 is a section on the line 6—6 of Fig. 3.

Figs. 7 and 8 are sectional views at right angles of another modified form of the device.

Figs. 9 and 10 are sectional views with parts in elevation illustrating the application of a colored segmental disk.

As shown on the drawings:

The reference numeral 10 refers to a handle of any suitable material on one end of which is mounted a U-shaped frame 11 apertured at each end for a pin or pivot bolt 12. Between the ends of the U-frame suitable spacers or hubs 13 are rotatably mounted on the pivot pin. Between the hubs or spacers 13 a gyroscopic or weighted balanced wheel 14 is freely rotatable. This wheel comprises an apertured disc having a heavy rim 15. As shown, this rim is formed of an annular ring of metal, over which the material of the disc is bent or spun to form a substantial wheel with the moment of inertia as large as possible. This disc 14 is preferably dished so that the bearing on the pin will be central with respect to a cross-section of the wheel rim.

A bell 16 or other sound producing means is attached to the frame in any convenient way in a position to be struck by the flying end of a cord 17 used to impart motion to the wheel 14. The cord is preferably attached to a ring 18 free on one of the spacers 13, although it may be looped and tied about the spacer itself as shown in Fig. 3. In either case the cord is not immovably secured to the spacer, friction of the cord over the rim of the wheel being sufficient to impart motion thereto when the balance of the cord is wound upon the other spacer and the free end of the cord is pulled.

The modification, shown in Figs. 7 and 8 does not differ in principle from the other, from the changes comprising placing the handle in line with the plane of the wheel and adding a boss 19 to the frame for the purpose of utilizing or demonstrating the gyroscopic effect of the rapidly rotating wheel 14.

The operation of this toy is comparatively simple, an advantage when consider-

ing the youth of the average user. The string or cord is always in place ready to be used to reverse the spinning wheel, yet holding the cord will not stop the wheel.

5 Assuming that an initial rotative motion has been given the wheel, simply bending the loosely held cord over the rim 15 will frictionally engage the cord, (see Figs. 1 and 4) and wind it upon the spacer at the other 10 side of the wheel, as shown in Figs. 2 and 5. To assist this action, a notch 20 may be formed in the rim to pick up the cord, but this is not essential. A sudden pull on the 15 end of the cord so wound up will reverse the direction of motion of the wheel whereupon the cord can be wound up in a reverse direction. By releasing the end of the cord it swings out due to centrifugal force, striking the bell at each revolution of the wheel.

15 20 A knot 22 in the end of the cord will intensify the sound produced.

A modification of this mode of operation is shown in Figs. 3 and 6, wherein the cord is shown looped about one spacer. It will 25 be evident that the ring 18 may be used if desired, the figures really being intended to illustrate two independent modifications. In these figures the cord is passed through an aperture 21 in the web of the wheel, having the effect of fastening the cord to the wheel. With this form the cord may be 30 pulled at predetermined intervals to reverse the wheel or released to cause striking of the bell, as heretofore described.

35 35 A plurality of apertures, such as 21, may be provided in the web so shaped as to give a humming or whistling music during rapid rotation of the wheel, if so desired. It should also be noted that the aperture 40 21 is placed so that it will be contacted by a knot 21^a, thus facilitating the effective engagement between the wheel and the propelling string. I attain a novel color blending effect by loosely mounting a disc member 45 23 on one of the spacers 13 said disk member being painted or otherwise impressed with bands of primary colors 24 and the web of the wheel 14 adjacent said disc member being also provided with bands of dis- 50 similar or preferably complementary colors 25. The relative rotation of the members 23 will be limited by the contact with the knot in the cord 17 as shown in Figs. 9

and 10 and the rapid relative rotation of the wheel 14 will act to cause variegated 55 color effects which are very striking.

I am aware that numerous details of construction may be varied through a wide range without departing from the principles of this invention, and I therefore do 60 not purpose limiting the patent granted otherwise than necessitated by the prior art.

I claim as my invention:

1. In a toy of the class described a handle, a frame, a pin passing through said frame, 65 a pair of spacers freely rotatable on said pin, and a rotatable wheel journalled on said pin between said spacers and a cord adapted to be wound on one of said spacers by said wheel, said cord being connected to 70 said wheel.

2. In a toy of the class described a handle, a frame, a pin passing through said frame, 75 a pair of freely rotatable spacers on said pin, a rotatable wheel journalled on said pin between said spacers, and a cord loosely secured around one of said spacers engaging said wheel and adapted to be wound upon the other of said spacers to impart motion to 80 said wheel.

3. In a toy of the class described a handle, a frame, a pin passing through said frame, 85 a pair of freely rotatable spacers on said pin, a rotatable wheel journalled on said pin between said spacers, a cord loosely secured around one of said spacers engaging said wheel and adapted to be wound upon the other of said spacers to impart motion to 90 said wheel, and a sound producing means located in a position to be struck by the free end of said cord when said cord is released after winding upon said spacer.

4. In a toy comprising a rotatable wheel and a suitable support therefor, a cord loosely surrounding the pivot of said wheel 95 and adapted to frictionally engage over said periphery on one side thereof passing axially over the periphery thereof to cause rotation thereof, said cord extending around said pivot on the other side of said wheel, 100 the end remaining free, and sound producing means on said support adapted to be struck by the free end of said cord.

In testimony whereof I have hereunto subscribed my name.

FRANK M. PIERCE.
